UNITED STATES PATENT OFFICE

CHARLES W. GORDON, OF PLEASANTVILLE, NEW YORK, ASSIGNOR TO THE SUPER-HEATER COMPANY, OF NEW YORK, N. Y.

BOILER

Application filed May 10, 1930. Serial No. 451,353.

The present invention relates to the art of steam generation and has as its principal object the provision of a convenient and efficient arrangement whereby the ratio of radiant heating surface to convection heating surface may be increased.

The novel features of my invention are pointed out with particularity in the appended claims. The invention itself, however, together with further objects and advantages, will best be understood from the following detailed description of a particular boiler and furnace embodying my invention taken in connection with the accompanying drawings in which

Fig. 1 is a vertical sectional view through a boiler and furnace in accordance with my invention taken on the line 1—1 of Fig. 2.

Fig. 2 is a vertical sectional view taken at right angles to the plane of Fig. 1, parts being broken away for purposes of illustration.

Recent practice in steam generation has tended toward operation of boilers and furnaces at high ratings, especially in the case of water tube boilers, but it has been found that operation at high ratings has often produced an undue rate of depreciation in the tubes subjected to direct radiation due to the combined effects of radiation and high temperature gases. It has been proposed to reduce the severity of the conditions to which the tubes nearest the fire are subjected by cooling somewhat the gases contacting with such tubes by radiation to vertical water walls. However, in the ordinary types of water tube boilers it has been found difficult to provide sufficient radiant receiving surface to permit the desired intensity of combustion in the furnace without high rate of deterioration of many of the ordinary generating tubes. In the drawings, I have illustrated an arrangement whereby the amount of the vertical radiant receiving surface necessary for accomplishing such object may be readily provided.

Referring to the drawings more in detail, 10 indicates a bank of horizontally inclined generating tubes extending between rear headers 12 and front headers 14, said headers being connected to a transverse horizontal

steam and water drum 16 by vertical downcomer nipples 18 and horizontal circulator nipples 20. Bank 10 is set above the furnace chamber 22. In order to cool the gases from furnace 22 by radiation before they strike the lower rows of tubes in bank 10, I divide the tubes of bank 10 into a convenient number of groups such as 10a, 10b and 10c by means of sets of vertical tubes 24, 24 extending through lanes between groups 10a, 10b and 10c and forming walls or partitions adapted to receive radiation and running down into chamber 22. Each group of tubes 24 extends horizontally in a direction transverse to the drum 16 from a point near the front headers 14 to a point near the rear headers 12. Walls 24a similar to walls 24 are provided also at the outer vertical sides of the groups 10a and 10c along the side walls of the furnace chamber 22. In the arrangement illustrated, water for the vertical tubes 24 and 24a is taken from the drum 16 by a row of nipples 26 which runs longitudinally of drum 16 below the water line therein. Nipples 26 incline downwardly and rearwardly from the drum to connect with a horizontal manifold 28 at the rear of the boiler setting. From the manifold 28 downcomer conduits 30, 30 conduct the water downwardly and then horizontally to points beneath the chamber 22, the lower ends of conduits 30 running parallel to the planes defined by the groups of vertical tubes 24 and 24a and lying intermediate such planes but below the lower ends of such vertical tubes. From the horizontal portions 31 of conduits 30 riser nipples 32 conduct the water upwardly and transversely to the interiors of lower horizontal manifolds 34, 34 parallel to conduit sections 31 and each of which connects with the lower ends of a given row of vertical tubes 24 or 24a. As shown, there are two sets of nipples 32 leading from each conduit portion 31 so that each of the conduits 30 is required to supply an equal number of vertical tubes 24 or 24a. The manifolds 34, as well as the conduit sections 31, lie below the floor of furnace chamber 22.

Tubes 24 and 24a extend vertically through the chamber 22 and alongside the groups of tubes forming bank 10 to connections with

upper manifolds 36, 36. Preferably, manifolds 36 are above the ordinary roof level of the boiler of the type employing generating tubes such as those illustrated in bank 10 and 5 are shown as lying above the horizontal circulator nipples 20. Upper manifolds 36 also run transverse to the drum 16 and in order to connect the upper manifolds into the drum most efficiently, I prefer to provide nipples 10 38, 38 which connect into the sides of the manifolds 36, at points spaced longitudinally of such manifolds and extend outwardly from the manifolds and then parallel to them so as to connect into the drum 16 at points 15 such as 40, 40 spaced longitudinally of the drum along a horizontal line. The steam from the tubes 24 is, therefore, taken out of the upper manifolds 36 at points distributed along the lengths of such manifolds and introduced 20 into the drum 16 somewhat equally along the length of the drum. Moreover, the steam and water from manifolds 36 are brought into drum 16 without weakening the shell of the drum so as to require reinforcement thereof as would be the case if the relatively large manifolds 36 were connected directly 25 into drum 16.

I prefer to provide also, front and rear water walls for the furnace chamber 22 composed of tubes 42 and 44 respectively. Such water walls are in common use, but I find that the circulatory system previously described in connection with the water walls 24 and 24a may be utilized in part in connection 30 with the water walls 42 and 44 although walls 24 and 24a are in planes at right angles to walls 42 and 44. As illustrated, the circulatory arrangement for water walls 42 and 44 comprises downcomer 35 conduits 46, 46, the upper ends of which connect into the ends of the manifold 28. Conduits 46 extend downwardly and forwardly along the sides of chamber 22 to points such as 48 midway of the sides of the furnace 40 chamber at which points conduits 46 divide into branches 46a and 46b which run respectively forwardly and rearwardly and downwardly so as to connect with the ends 45 of manifolds 42a and 44a which extend outside the walls of chamber 22 along its front and back respectively. Manifold 42a connects to the bottoms of tubes 42, and manifold 44a connects to the bottoms of tubes 44, and each of these manifolds is fed with water 50 at both ends. The tops of tubes 42 connect into the manifold 42b which runs parallel to the front wall of chamber 22. Each end of the manifold 42b connects into a riser 50 which extends upwardly and rearwardly to 55 a point at the level of the center of drum 16 but somewhat in the rear of such drum where it connects into a horizontal manifold 52 running parallel to the drum 16 and from which steam and water are conducted into the drum 60 by means of curved nipples 54 extending in

a row along the manifold 52 and connecting into the upper portion of the rear face of drum 16.

The upper ends of the rear water wall tubes 44 connect into a horizontal manifold 56 from which steam and water are conducted by riser nipples 58 running upwardly at the rear of the boiler and connecting at the upper ends into the lower face of the manifold 52. 75

The furnace for the installation above described is preferably fired by means of liquid or pulverized fuel, and the burners are set at the centers of burner apertures such as 60, 60 in the front wall of the furnace. The flames from the burners are directed rearwardly along the lanes midway between the vertical walls 24 and 24a which extend below the burners. The gases in the furnace chamber, therefore, radiate heat to the tubes 24 and 24a and thereby reduce their temperatures before striking the lower tubes of bank 10. Not only is the rate of deterioration of the tubes 10 thereby decreased, but the capacity of the boiler installation is greatly increased. 80 85 90

It will be seen that I have provided an arrangement for increasing the length of life of an ordinary water tube boiler at the same time increasing its capacity, but one which can be fabricated by methods now in common use. 95

I claim:

1. The combination in a boiler of a plurality of groups of generator tubes, said groups having vertical lanes therebetween, a steam and water drum transverse to said tubes and connected to both ends thereof, rows of vertical water tubes in said lanes between and extending well below said groups, and means connecting the tops and bottoms of said vertical tubes to said drum, said means for connecting the generator tubes to the transverse drum including substantially horizontal nipples above the generator tubes, 100 105 110 said vertical tubes extending through said horizontal nipples to points above said nipples, and said means connecting the vertical tubes to the drum including manifolds transverse to the steam and water drum. 115

2. The combination as set forth in claim 1 and in which a furnace chamber is provided below the generator tubes and the vertical tubes extend through the bottom of said chamber. 120

3. The combination in a boiler of a plurality of groups of generator tubes, said groups having vertical lanes therebetween, a steam and water drum transverse to said tubes, means connecting both ends of said tubes to said drum and including substantially horizontal nipples above said generator tubes, rows of vertical water tubes extending in said lanes between and well below said generator tubes and above said nipples, mani- 125

- 5 folds transverse to said drum and connected to the upper ends of said vertical tubes, circulator nipples connected into said manifolds at longitudinally spaced points along the manifolds and connected into said drum at longitudinally spaced points along the drum, and means connecting said drum to the lower ends of said vertical water tubes.
- 10 4. The combination in a boiler of generator tubes arranged in groups separated by vertical lanes, a steam and water drum transverse to said tubes, means connecting both ends of said tubes to said drum to provide for circulation therethrough and including substantially horizontal nipples above said generator tubes, vertical tubes in the lanes between said generator tubes and extending above said nipples and also bounding two sides of said generator tubes parallel to said lanes, means connecting both ends of said vertical tubes to said drum to provide for circulation therethrough, a furnace chamber below said generator tubes through which some of said vertical tubes extend and which has two of its 25 walls faced by other of said vertical tubes, additional vertical water tubes on the inner surface of another wall of said furnace chamber, and means connecting both ends of said additional water tubes into said drum to provide for circulation therethrough.
- 30 5. The combination as set forth in claim 4 and in which the means for connecting the lower ends of the additional vertical water tubes with the drums and the means for connecting the lower ends of the water tubes in the lanes of the generator tubes have a header in common which is adjacent the steam and water drum and substantially parallel thereto, and circulator nipples connecting said header and the steam and water drum and spaced longitudinally along the drum and header.
- 35 6. The combination in a boiler of a plurality of groups of generator tubes separated by vertical lanes, a steam and water drum transverse to said tubes, means connecting both ends of said tubes to said drum to provide for circulation therethrough, a furnace chamber beneath said generator tubes, vertical water tubes in said lanes and at two sides of said generator tubes and extending from a level above the generator tubes to a level below said furnace chamber, manifolds transverse to said drum and connecting the lower 40 ends of said vertical water tubes in groups, a header adjacent said drum and parallel thereto, circulator nipples connecting said header to said drum below the water line in the drum and spaced longitudinally of the drum and header, conduits extending downwardly from said header to a point below said furnace chamber and running parallel to said manifolds at their lower ends, nipples connecting the lower ends of said conduits to said manifolds and spaced longitudinally of the manifolds and lower ends of the conduits, and means connecting the upper ends of said vertical water tubes to said steam and water drum.
- 45 7. The combination in a boiler of a plurality of groups of generator tubes having vertical lanes between the groups, a steam and water drum, means for connecting said drum to both ends of said tubes including substantially horizontal nipples above said generator tubes, a furnace below said tubes, firing means for said furnace, rows of vertical water tubes in said lanes and extending into said furnace below the level of said firing means, and means connecting the tops and the bottoms of said vertical tubes to said drum.
- 50 8. The combination as set forth in claim 7 and in which the vertical water tubes extend down as far as the bottom of the furnace.
- 55 9. The combination in a boiler of a plurality of groups of generator tubes having vertical lanes between the groups, a steam and water drum connected to both ends of said tubes, a furnace below said tubes, firing means for said furnace, rows of vertical water tubes in said lanes and extending into said furnace below the level of said firing means, means for connecting the tops of said vertical tubes to said drum, and means for connecting the bottoms of said vertical tubes to said drum including downcomer connections the lower ends of which extend parallel to the planes of the vertical tubes intermediate said planes, manifolds at the lower ends of the vertical water tubes and horizontally extending nipples connecting the lower ends of said downcomers with said manifolds.
- 60 10. The combination in a boiler, of a plurality of groups of vertical water tubes spaced horizontally and lying in parallel planes, a steam and water drum extending transversely to the planes of said groups, connections between the upper ends of said tubes and said drum, a header parallel to said drum and connected thereto, manifolds at the bottoms of said vertical tubes and conduits connected at their upper ends to said header and each conduit connected at its lower end to two of said manifolds.
- 65 11. The combination in a boiler of groups of vertical water tubes arranged in parallel planes, a steam and water drum extending transversely of the planes of said tubes, means connecting the upper ends of said tubes to said drum, a furnace having two side walls lined by groups of said tubes, vertical tubes screening the front and rear walls of said furnace, means including a common header for connecting the upper ends of said last mentioned tubes to said drum, means including a header for connecting the lower ends of said first mentioned groups of tubes to said drum, and means including said last mentioned header for connecting the lower 70 ends of said first mentioned groups of tubes to said drum.
- 75 12. The combination in a boiler of a plurality of groups of generator tubes having vertical lanes between the groups, a steam and water drum, means for connecting said drum to both ends of said tubes including substantially horizontal nipples above said generator tubes, a furnace below said tubes, firing means for said furnace, rows of vertical water tubes in said lanes and extending into said furnace below the level of said firing means, and means connecting the tops and the bottoms of said vertical tubes to said drum.
- 80 13. The combination in a boiler of a plurality of groups of generator tubes having vertical lanes between the groups, a steam and water drum connected to both ends of said tubes, a furnace below said tubes, firing means for said furnace, rows of vertical water tubes in said lanes and extending into said furnace below the level of said firing means, means for connecting the tops of said vertical tubes to said drum, and means for connecting the bottoms of said vertical tubes to said drum including downcomer connections the lower ends of which extend parallel to the planes of the vertical tubes intermediate said planes, manifolds at the lower ends of the vertical water tubes and horizontally extending nipples connecting the lower ends of said downcomers with said manifolds.
- 85 14. The combination in a boiler of a plurality of groups of generator tubes having vertical lanes between the groups, a steam and water drum connected to both ends of said tubes, a furnace below said tubes, firing means for said furnace, rows of vertical water tubes in said lanes and extending into said furnace below the level of said firing means, means for connecting the tops of said vertical tubes to said drum, and means for connecting the bottoms of said vertical tubes to said drum including downcomer connections the lower ends of which extend parallel to the planes of the vertical tubes intermediate said planes, manifolds at the lower ends of the vertical water tubes and horizontally extending nipples connecting the lower ends of said downcomers with said manifolds.
- 90 15. The combination in a boiler, of a plurality of groups of vertical water tubes spaced horizontally and lying in parallel planes, a steam and water drum extending transversely to the planes of said groups, connections between the upper ends of said tubes and said drum, a header parallel to said drum and connected thereto, manifolds at the bottoms of said vertical tubes and conduits connected at their upper ends to said header and each conduit connected at its lower end to two of said manifolds.
- 95 16. The combination in a boiler of groups of vertical water tubes arranged in parallel planes, a steam and water drum extending transversely of the planes of said tubes, means connecting the upper ends of said tubes to said drum, a furnace having two side walls lined by groups of said tubes, vertical tubes screening the front and rear walls of said furnace, means including a common header for connecting the upper ends of said last mentioned tubes to said drum, means including a header for connecting the lower ends of said first mentioned groups of tubes to said drum, and means including said last mentioned header for connecting the lower 100 ends of said first mentioned groups of tubes to said drum.
- 100 17. The combination in a boiler, of a plurality of groups of vertical water tubes spaced horizontally and lying in parallel planes, a steam and water drum extending transversely to the planes of said groups, connections between the upper ends of said tubes and said drum, a header parallel to said drum and connected thereto, manifolds at the bottoms of said vertical tubes and conduits connected at their upper ends to said header and each conduit connected at its lower end to two of said manifolds.
- 105 18. The combination in a boiler of groups of vertical water tubes arranged in parallel planes, a steam and water drum extending transversely of the planes of said tubes, means connecting the upper ends of said tubes to said drum, a furnace having two side walls lined by groups of said tubes, vertical tubes screening the front and rear walls of said furnace, means including a common header for connecting the upper ends of said last mentioned tubes to said drum, means including a header for connecting the lower ends of said first mentioned groups of tubes to said drum, and means including said last mentioned header for connecting the lower 110 ends of said first mentioned groups of tubes to said drum.
- 110 19. The combination in a boiler of groups of vertical water tubes arranged in parallel planes, a steam and water drum extending transversely to the planes of said tubes, means connecting the upper ends of said tubes to said drum, a header parallel to said drum and connected thereto, manifolds at the bottoms of said vertical tubes and conduits connected at their upper ends to said header and each conduit connected at its lower end to two of said manifolds.
- 115 20. The combination in a boiler of groups of vertical water tubes arranged in parallel planes, a steam and water drum extending transversely of the planes of said tubes, means connecting the upper ends of said tubes to said drum, a furnace having two side walls lined by groups of said tubes, vertical tubes screening the front and rear walls of said furnace, means including a common header for connecting the upper ends of said last mentioned tubes to said drum, means including a header for connecting the lower ends of said first mentioned groups of tubes to said drum, and means including said last mentioned header for connecting the lower 120 ends of said first mentioned groups of tubes to said drum.
- 120 21. The combination in a boiler of groups of vertical water tubes arranged in parallel planes, a steam and water drum extending transversely to the planes of said tubes, means connecting the upper ends of said tubes to said drum, a furnace having two side walls lined by groups of said tubes, vertical tubes screening the front and rear walls of said furnace, means including a common header for connecting the upper ends of said last mentioned tubes to said drum, means including a header for connecting the lower ends of said first mentioned groups of tubes to said drum, and means including said last mentioned header for connecting the lower 125 ends of said first mentioned groups of tubes to said drum.
- 125 22. The combination in a boiler of groups of vertical water tubes arranged in parallel planes, a steam and water drum extending transversely of the planes of said tubes, means connecting the upper ends of said tubes to said drum, a furnace having two side walls lined by groups of said tubes, vertical tubes screening the front and rear walls of said furnace, means including a common header for connecting the upper ends of said last mentioned tubes to said drum, means including a header for connecting the lower ends of said first mentioned groups of tubes to said drum, and means including said last mentioned header for connecting the lower 130 ends of said first mentioned groups of tubes to said drum.

ends of the second mentioned groups of tubes to said drum.

12. The combination in a boiler of a plurality of groups of vertical water tubes arranged in spaced parallel planes, a furnace chamber two sides of which are bounded by a pair of said groups of tubes, a steam and water drum extending transverse to the planes of said groups and near the upper ends of said groups, manifolds transverse to said drum and each connected to the lower ends of the tubes in one of said groups, a header adjacent to said drum and parallel thereto, means connecting said header to said drum, conduits extending downwardly from said header to points below said furnace and running parallel to said manifolds at their lower ends, nipples connecting the lower ends of said conduits to said manifolds and spaced longitudinally of the manifolds and lower ends of the conduits, and means connecting the upper ends of said vertical water tubes to said steam and water drum.

CHARLES W. GORDON.
